UNITED STATES PATENT OFFICE.

NATHAN H. SUREN, OF NEEDHAM, MASSACHUSETTS, ASSIGNOR, BY MESNE ASSIGNMENTS, TO THE GAMEWELL COMPANY, OF NEWTON, MASSACHUSETTS, A CORPORATION OF MASSACHUSETTS.

SIGNALING MECHANISM.

Application filed December 7, 1920. Serial No. 428,952.

This invention relates to signaling mechanism comprising mechanically operable electrically controlled circuit changing mechanism and more particularly to such mechanisms as are suited for use in auxiliary fire alarm signal initiating stations.

An object of this invention is to provide a signaling mechanism adapted to be set by a slow moving part to suitably actuate contacts forming part of a signaling circuit current path, and to maintain such contacts in said actuated condition for a predetermined brief period, and thereupon restore such contacts to their original condition.

A further object of this invention is to provide a mechanism of the character described which is so responsive to current flow in the signaling circuit controlled thereby that, should such device actuate said signaling circuit contacts at a time when there is no current flow in such signaling circuit, said contacts will be maintained in said actuated condition until the expiration of such a predetermined brief period subsequent to the commencement of the next succeeding current flow in said circuit.

A further object is to provide, in such a mechanism, means whereby,—when such mechanism has been set to effect the actuation of the signaling contacts controlled thereby,—said mechanism will be rendered unresponsive to further attempts to so set same until thereafter manually released or reset.

A further object is to provide such a mechanism having a renewable frangible panel normally preventing access to a manually operable member thereof, in which the renewal of said frangible panel can not be effected without releasing or resetting such mechanism; to the end that said mechanism will at all times be in operative condition when the frangible panel thereof is intact.

Other objects are to provide such a mechanism which is durable, positive and reliable in action, inexpensive to manufacture and maintain, and which is operable in a simple and obvious manner.

Still other objects together with their in-

herent advantages will be in part obvious and in part specifically set forth in the following specification, and more fully pointed out in the claims.

For the purpose of illustrating the various features of this invention, an embodiment thereof is shown by the annexed drawings and hereinafter more fully described, which embodiment is particularly suited for use in connection with fire alarm systems such as that shown by my copending application filed April 4th, 1919, Serial No. 287,502, Patent No. 1,503,439, issued July 29th, 1924, and by my copending application Serial No. 483,222 filed concurrently herewith.

Similar reference characters denote like parts throughout the accompanying drawings, in which.

Figure 1 is a front elevation of the exterior of a fire alarm station embodying this invention;

Fig. 2 is a side elevation with portions broken away and shown in section to disclose interior parts of the fire alarm station of Fig. 1;

Fig. 3 is a fragmentary plan view to be referred to;

Fig. 4 is a sectional view of certain of the parts shown by Fig. 3 and taken along the line 4—4 thereof;

Fig. 5 is a front elevation of the signal initiating device of the fire alarm station of Fig. 1, the various parts being shown in their respective normal positions, certain of the parts being broken away to more clearly disclose the operating mechanism;

Fig. 6 is a front elevation of certain of the parts of Fig. 5 shown during the first operative step thereof;

Fig. 7 shows the parts of Fig. 6 at the second operative step thereof;

Fig. 8 shows the parts of Fig. 6 at the third operative step thereof;

Figs. 9, 10 and 11 are fragmentary views to be referred to;

Fig. 12 is a side elevation of the cover shown in Figs. 1 and 2, with the chamber housing and its clamping nut shown in detached relation thereto;

Fig. 13 is a sectional plan view of certain

of the parts shown in Fig. 2, taken on line 13—13;

Fig. 14 is a front elevation partly in section, showing the application of certain of the parts of Figs. 1 to 13 in an embodiment of this invention adapted for operation by a change in liquid level or pressure;

Fig. 15 is a front elevation of an embodiment of this invention adapted for operation by a thermostatically controlled device, but otherwise similar to Fig. 14; and

Fig. 16 is a sectional view of certain of the parts of Fig. 15, taken on line 16—16.

Referring to Figs. 1 and 2; the box or case 21 is provided for containing the signal initiating device hereinafter described, and lugs 22 and 23 are provided at the top and bottom of said case for the purpose of facilitating connection thereto of conduit pipes for leading circuit conductors to the signal initiating device contained therein, and the front opening of said case has the annular flange 24 for supporting a suitable door or cover.

25 The cover 25 is fitted into the front opening of the case 21 to rest against the flange 24. A stationary lug 26 and a latch bolt 27 are carried by the cover 25 to engage the flange 24 for the purpose of securing said cover in position over the opening of the front of the case 21.

An opening 28 is provided through the cover 25 to afford access to the operating handle 29 of a signal initiating device which 35 will be hereinafter more fully described.

The rear side of the cover 25 is recessed as indicated at 30 along the top and side edges of the opening 28 for receiving a suitable frangible panel 31.

40 A rearwardly extending ledge 32 is carried by the cover 25, which ledge is disposed substantially parallel to and situated somewhat above the upper edge of the opening 28 and is of such length and width as to be suited to form the upper wall of a chamber for the operating handle 29.

The latch bolt 27 is arranged to slide through the ledge 32 and the guide 33 and carries a crossbar 34 which moves between 50 said guide 33 and the abutment 35 and thereby serves to limit the travel of said bolt. The spring 36 is applied between the ledge 32 and the crossbar 34 so as to constantly urge the bolt 27 for movement thereof in the direction of the flange 24.

The rear side of the upper end of the bolt 27 is beveled so that said bolt 27 may be forced out of the path of the flange 24 by engagement therewith during the application of the cover 25 to the case 21, and the ends of the crossbar 34 extend from the opposite sides of the bolt 27 and engage identical guide faces, one of which is shown at 37, so that said bolt cannot so rotate as to 65 bring the beveled upper end thereof in unin-

tended relation with the flange 24. In order that the fastening means which comprises the bolt 27 shall be operable to permit unfastening thereof and so positioned that when the cover 25 is fastened in the case 21 and a frangible panel 31 is secured in the opening 28 therein, said cover cannot be unfastened without first breaking such panel,—a knob 38 is provided at the lower end of the said bolt which knob is so positioned that access thereto is normally obstructed by the panel 31, and so that, when said panel is not in position, said knob will be readily accessible through the opening 28.

Pins, such as the pin 39, project from the 80 ends of the ledge 32 and form pivots around which may swing the side walls 40 and 41 of a frangible panel holding frame or housing.

The side walls 40 and 41 are connected at 85 the lower ends thereof by the base wall 42, and said walls form the side and base walls of a chamber for the operating handle 29. The upper ends of the walls 40 and 41 have slots formed therein to receive the pins 39, 90 (see Fig. 12), and the wall 42 carries an ear 43 to receive the stud 44, which stud projects rearwardly from the cover 25. The nut 45 is threaded on the stud 44 for the purpose of clamping the ear 43 against the 95 rear side of the cover 25. The front edges of the walls 40 and 41 overlap the recess which is formed along the sides of the opening 28, and thus serve to retain the frangible panel 31 therein.

100 The plate 46 is secured to the frame bar 47 by means of the screws 48, 48; said bar 47 being a part of the supporting frame of the signal initiating device, as shown by Figs. 5, 11 and 13. The central portion of the bar 47 is shown broken away in Figs. 5 and 11 to better disclose the mechanism which it overlies. When the cover 25 is secured to the case 21 in its intended position, the plate 46 forms the rear wall of the chamber for the operating handle 29, an opening being provided through said plate through which the handle-supporting shaft 49 projects into such chamber.

115 A pin 50 is carried by the outer side of the wall 40, which pin projects adjacent to the under side of the post 51 behind the enlarged head 52 carried at the outer end of said post, so that the movement of said pin 50 incident to placing the cover in position 120 upon or removal thereof from the case 21 will cause said pin to engage said head so as to suitably raise the post 51 for a purpose which will be hereinafter more fully described.

125 The shaft 49 has a bearing in the bar 47 immediately behind the plate 46, and the rear end of said shaft has a bearing in the rear plate 53 (see Figs. 2, 3, 4 and 13), the notched disc 54 is firmly secured to the 130

shaft 49 near the rear side of the bar 47, being spaced therefrom by the washer 55, and the sleeve 56 is loosely mounted upon the shaft 49 and carries the channel flange 57. (See Figs. 4 and 9.)

The spiral spring 58 encloses the sleeve 56, one end of said spring being secured to the hub of the disc 54 and the other end of said spring being secured to the flange 57, so that energy imparted to the shaft 49 and the disc 54 may be transmitted, through said spring 58, to the flange 57. The drum 59 is mounted on the sleeve 56 by means of the posts 60 and 61, the ends of which posts rest against the front side of the flange 57, said drum being secured to said flange by means of attaching screws 62 passing through the flange and into said posts, as shown by dotted lines in Figs. 3 and 9. One end of the drum 59 is of enlarged diameter and has escapement teeth 63 formed in the periphery thereof, and the other end of said drum carries the cam faces 65. In the interests of clearness, the cam portion of the drum 59 is shown independently of said drum in Figs. 6, 7 and 8; and the portions of said faces which extend behind the disc 54 are indicated by dotted lines in Fig. 5.

The channel of the flange 57 extends transversely to the axis of the shaft 49 in the rear side of said flange, and said channel is of such width and depth as to receive the detent plate 66 for free movement lengthwise of said channel. A cam 67 is secured to the shaft 49 within an opening in the detent plate 66, which opening is of such width, (measured along the line of movement of such plate along the channel in the flange 57) as to permit said cam to rotate freely within said opening; and said opening is elongated transversely to said line of movement so as to permit said cam to swing to one side of the center of rotation thereof transversely to the channel in the flange 57 incidentally to movement of said cam such as will impart movement to the detent plate 66 lengthwise of said channel.

A toothed member 68 is secured to the rear plate 53, immediately behind the detent plate 66, the teeth of said member being so formed that a lug 69 carried by the rear side of said plate may be moved into and out of engagement with the radial faces of the teeth of said member by the rotation of the cam 67. (See Fig. 10.)

It should be noted that Fig. 9 is a rear view of the drum 59, showing the escapement teeth 63, and showing the flange 57, the plate 66 and the cam 67 in position thereon; while Fig. 10 is a front view of the plate 66, and the member 68; the lug 69 and obscured portions of said member being indicated by dotted lines therein.

In order to suitably limit the extent of

each step of the actuation of the handle 29, and for the further purpose of preventing effective actuation thereof other than in clockwise direction, the disc 54 is so notched as to provide projections which are best shown in Figs. 5 and 11, one side of each of said projections is arranged for cooperation with the free end of the latch 70 and the other side of each of said projections is arranged for cooperation with the free end of the ratchet dog 71. The sides of the projections which are arranged for engagement by the latch 70 will be hereinafter referred to as the "advancing faces" thereof, and the sides of said projections which are arranged for engagement by the dog 71 will be hereinafter referred to as "receding faces."

The latch 70 is pivoted on the screw 72, which screw is secured to a stepped face of the frame bar 47, as best shown in Figs. 5 and 11. A slot 73 is formed in the pivoted end of the latch 70, so that said latch may move substantially lengthwise thereof in addition to swinging around said pivot screw 72; the lengthwise movement of said latch 70 is limited by the end 74 of the slot 73 (see Fig. 5) and by the pin 75 which closes the other end of said slot. A spring 76 is so applied to the latch 70 as to tend to swing the free end of said latch into engagement with the periphery of the disc 54, and so as to tend to slide said latch lengthwise in the opposite direction to that of the movement imparted thereto by the engagement of projections 77 of the disc 54 with the free end thereof.

From the foregoing it will be seen that the cooperation between the latch 70 and the disc 54 is such that, when the said disc is rotated in a clockwise direction until the advancing face of one of the projections 77 thereof is brought against the free end of said latch 70, said latch will be moved substantially lengthwise thereof until the end 74 of the slot 73 is brought against the screw 72, whereupon the rotation of the disc 54 will be arrested; and that if the disc 54 is then held stationary and the free end of the latch 70 is swung out of engagement with said disc, said latch will be moved by the spring 76 so that the free end of said latch will extend over the projection 77. Said latch may then be released and the free end thereof will rest upon said projection, so that the disc 54 may be again moved until the advancing face of the next projection 77 correspondingly engages and moves the latch 70.

In order to prevent reverse movement of the handle 29 and the disc 54, after such rotation thereof as to cause engagement and movement of the latch 70, as just described, a ratchet mechanism is provided which comprises the dog 71, which is pivoted at 78 and which has the spring 79 so applied

thereto as to tend to swing the free end of said pawl into the path of the projections 77; said dog 71 being of such length that, when the advancing face of one of the projections 77 has engaged the free end of the latch 70 and so moved said latch as to bring the end 74 of the slot 73 against the screw 72, said projection 77 will be withdrawn from the path of the dog 71 and the free end 10 of said dog will be moved into the path of the receding face of said projection so as to prevent reverse movement thereof.

The post 51 is secured to the latch 70 between the free end thereof and the pivot 72, 15 so that whenever said post is raised by the pin 50, (as hereinbefore described) the free end of said latch will be withdrawn from the path of the projections 77.

A bell-crank lever 80 is pivoted at 81 and 20 is mounted in such relation to the cam faces 65 that the shoulder 82 carried by said lever may suitably engage said faces. Said shoulder is so positioned with relation to such 25 faces that when the handle 29 and disc 54 are rotated an angular distance corresponding to that between the advancing faces of adjacent projections 77, the horizontal member of the lever 80 will be elevated by one 30 of the cam faces 65 and said cam face will thereupon be withdrawn from the path of the shoulder 82.

An escapement pallet 83 (see Fig. 5) is mounted upon a suitable pivot in position to 35 suitably engage the escapement teeth 63 so as to form a governor for regulating the speed of rotation of said teeth and the parts movable therewith.

The separately insulated resilient signaling contacts 84, 85 and 86 are carried by the 40 insulating block 87, the contact 85 being mounted between the contacts 84 and 86, and the free end of said contact 85 extends beyond the ends of the contacts 84 and 86 45 into the path of the insulating spacer 88 carried by the downwardly extending member of the bell-crank lever 80. Said contact 85 is so formed that the tension thereof constantly urges it into engagement with the contact 86, and the length of the spacer 88 is 50 such that when the horizontal member of the bell-crank lever 80 is lifted by one of the cam faces 65 said spacer will move the contact 85 away from the contact 86 and against the contact 84, and so that when the shoulder 82 is resting upon a depressed portion 55 of the cam faces 65 (see Figs. 5 and 6) the contact 85 will be permitted to move into engagement with the contact 86.

From the foregoing it will be seen that the 60 handle 29, shaft 49, and the parts numbered 54 to 88 inclusive, provide a signal initiating device having a definite cycle of action and responsive to a manually operable member thereof. It will also be seen that the signaling contact 84, 85 and 86 are constantly 65

urged to assume a predetermined relationship and are responsive to the actuation of an operating member (the drum 59 carrying the cam face 65) of said signal initiating device to momentarily revise the relationship of said contacts during the actuation of such operating member.

Such operating member and the parts co-operating therewith, are arranged to serve as quick acting mechanism for momentarily 75 causing a revision of the relationship of said contacts.

Although the manually operable handle 29 is shown in the accompanying drawings and hereinbefore described, it should be understood that a member correspondingly operable by other means might be substituted therefor, as, for example, a member operable thermostatically or by liquid level or pressure. In any event, actuating mechanism is provided comprising a setting member and operating mechanism movable thereby for suitably actuating said contacts.

Fig. 14 illustrates an embodiment of this invention in which a ratchet wheel 101, arranged so as to be operable by liquid level or pressure, is substituted for the handle 29 of Figs. 1 to 8 and Fig. 11. The operation of said ratchet wheel is accomplished by means of the lever 102, which is pivoted 95 at 103 to plate 104, and carries a pawl 105 arranged for suitably engaging said ratchet wheel. The cylinder 106 is secured to the case 21', and is arranged for connection of a source of fluid pressure thereto. A piston 107 is mounted in the cylinder 106 to be moved by the fluid pressure therein, and said piston is connected to the lever 102 by means of the link 108 so that when said piston 107 is raised by fluid pressure within 105 said cylinder, the movement thereof will cause lever 102 to swing in a clockwise direction around the pivot 103 so that the pawl 105 will impart suitable rotary movement to the ratchet wheel 101.

Fig. 15 illustrates an embodiment of this invention in which a ratchet wheel 101, arranged for responsiveness to a thermostatically controlled device, is substituted for the handle 29. A weight 109 suspended by a 115 fusible link 110 from the underside of the case 21" is so connected by a cord or wire 111 to the lever 102', that upon the fusing of said link, the weight 109 will be permitted to drop, and will thereupon act 120 through the cord or wire 111 to move lever 102' in a clockwise direction around its pivot 103 until it strikes the stop 112, thus causing the pawl 105 to rotate the ratchet wheel 101. Inasmuch as such operation of said ratchet wheel will be quickly accomplished, the cam faces 65 and the ratchet wheel or operable member 101 are fixed upon the shaft 49, so as to move together (as shown by Fig. 16) without the 130

use of the storage device and quick acting mechanism (comprising spring 58, escapement teeth 63 and pallet 83) and the detent mechanism (comprising the flange 57, 5 plate 66, cam 67 and member 68).

In embodiments of this invention such as those shown by Figs. 14 and 15, substitution may be made for the cover 25 shown by Figs. 1, 2, 12 and 13, by the use of a cover 10 such as 25' shown by Fig. 14; which cover 25' is not provided with a frangible panel and associated parts such as form part of the cover 25. The cover 25' is hinged to the case 21' at 113, and is provided with 15 a projection 114 for suitably engaging the enlarged head of the pin 51, carried by the latch 70, so that when said cover is removed from or replaced upon the case 21', said projection 114 will cause the latch 70 to 20 be so raised as to unlock the setting member (as hereinbefore more fully described). Means, such as the lock 115, may be provided for securing the cover 25' in position upon the case 21'.

25 In order that a setting member adapted for rapid or slow operation thereof (such as the manually operable handle 29) may assure uniformly quick action of such operating mechanism as the drum 59, the cam 30 faces 65 thereof and the shoulder 82 operable thereby, a storage device is provided comprising the spring 56, shown in Fig. 4, for imparting to said operating mechanism the actuating energy imparted to said device by said setting member.

Magnetically controlled mechanism is provided for progressively governing the restoration of the signaling contacts 84, 85 and 86 from the abnormal or altered relationship imparted thereto incident to the rotation of the cam faces 65 to the normal relationship thereof. Such magnetically controlled mechanism comprises the electromagnet 89, the armature 90 pivoted at 31 45 and having the retractile spring 92 therefor; and a step by step escapement controlled by said armature and governing such return movement of said bell-crank lever 80. Said step by step escapement comprises the 50 upwardly projecting spear-head 93 carried by the free end of the horizontal member of the bell-crank lever 80 and the ledges 94 and 95 carried by the armature for engagement therewith; a stop post 96 being provided for limiting the extent of the travel of the armature 90 away from the pole of the magnet 89. The ledge 94 is so positioned that, when the horizontal member of the bell-crank lever 80 has been lifted by 55 one of the cam faces 65, said ledge may engage one side of the spear-head 93 and thereby prevent such movement of said lever as would permit the contact 85 to move away from the contact 84. The ledge 95 is so positioned that when the ledge 94 has been

withdrawn from the path of the spear-head 93 the bell-crank lever 80 will be permitted to move far enough in response to gravity and to the tension of the contact 85 applied through the spacer 88 to the downwardly extending portion of said lever as to allow said contact to move away from the contact 84, whereupon the ledge 95 will so engage the other side of the spear-head 93 as to prevent such further movement of 70 said lever 80 as would permit the contact 85 to move into engagement with the contact 86; thus establishing a third or intermediate relationship of said contacts.

Conductors such as 97 and 98 of a suitable 80 signaling circuit may be connected to the contacts 85 and 86, respectively, and conductors 99 and 100 connect the ends of the windings of the electromagnet 89 to the contacts 84 and 86 respectively. From the foregoing it will be seen that a current path is normally provided between the conductors 97 and 98 and that a normally open branch current path is provided through the conductor 99, the winding of the electromagnet 90 89 and the conductor 100 to the contact 84. It will be further seen that, in response to the actuation of the bell-crank lever 80, such normally closed path will be broken and the normally open branch current path will 95 be closed between the contacts 84 and 85.

The number and arrangement of the signaling circuit contacts may be varied to suit the needs of various types of signaling circuits, the arrangement shown and hereinbefore described being particularly suited for use in connection with fire alarm systems such as that shown by my copending applications hereinbefore referred to.

The operation of the signaling mechanism 105 shown by the accompanying drawings and hereinbefore described is as follows:

When the parts are in normal position, the cover 25 and frangible panel 31 serve as a guard for protecting the manually operable member 29 from unauthorized actuation; the disc 54 is positioned as shown in Figs. 5 and 11, one of the receding radial faces of a projection 77 of said disc being engaged by the dog 71 so as to prevent counterclockwise movement of said disc; the free end of the latch 70 rests upon the top of the projection 77, (as shown in Fig. 5) the left-hand or receding radial face of which is engaged by the dog 71; the bell-crank lever 80 is positioned as shown in Fig. 5, and the contact 85 therefore rests against the contact 86; the lug 69 engages one of the radial faces of the member 68 (as shown by Fig. 10); and the energy-storage spring 58 is under 110 some tension, which tension is urging rotation of the disc, 54, shaft 49 and handle 29 in counterclockwise direction (such rotation being restrained by the dog 71) and is urging 115 rotation of the channel flange 57 in 120 some tension, which tension is urging rotation of the disc, 54, shaft 49 and handle 29 in counterclockwise direction (such rotation being restrained by the dog 71) and is urging 125 rotation of the channel flange 57 in 130

clockwise direction, which rotation is restrained by the engagement of the lug 69 (carried by the plate 66 within the channel of said flange) with a tooth of the member 68.

If the frangible panel 31 is broken, as by a blow from a glass-breaking hammer such as is ordinarily provided for use with a signal initiating station such as that shown in Fig. 1, the fragments of said panel will slide out of the chamber containing the handle 29, as the lower wall of said chamber is devoid of any projection or depression such as would tend to retain such fragments, and the base wall 42 and the forwardly inclined portion of the plate 46 are arranged at such an angle as to tend to cause frangible panel fragments resting thereupon to slide outwardly.

After breaking the frangible panel, as just described, access is afforded to the handle 29. If it is desired to transmit a signal through the circuit connected to the signal initiating device by the conductors 97 and 98, the handle 29 should be grasped and rotated as far as it will go in a clockwise direction. During such rotation of the handle 29, additional tension will be imparted to the spring 58, by tending to unwind or expand same, and the rotation of the cam 67 will gradually move the lug 69 out of the path of the teeth of the member 68. When the rotation of the handle 29 has continued for substantially one-quarter of a revolution thereof, the advancing face of one of the projections 77 will engage the free end of the latch 70 and move said latch substantially lengthwise thereof, until the end 74 of the slot 73 engages the screw 72, thereby arresting the rotation of the disc 54 and the handle 29. During movement of the latch 70 by one of the projections 77, as just described, such projection will withdraw from the path of the free end of the dog 71, and said dog will thereupon be moved by the spring 79 so as to prevent reverse or counterclockwise movement of the disc 54 and handle 29; such action of the dog 71 taking place before the latch 70 has been so moved as to bring the end 74 of the slot 73 against the screw 72.

During rotation of the disc 54 between the point at which a projection 77 is withdrawn from the path of the dog 71 and the termination of the movement thereof, as just described,—the cam 67 will move the plate 66 so as to carry the lug 69 out of the path of the teeth of the member 68, the flange 57 and parts moving therewith will thereupon be rotated in a clockwise direction for substantially one-quarter of a revolution thereof by the energy stored in the spring 58, and the speed of such revolution will be governed by the engagement of the escapement pallet 83 with the escapement teeth 63.

During such movement, the cam 67 will be stationary and the detent plate 66 will be rotated around said cam by the channel flange 57, so as to cause the lug 69 to be moved into engaging relation with the next tooth of the member 68 and thereby arrest the rotation of the operating mechanism parts at the desired point.

During the rotation of the channel flange 57, as just described, the cam faces 65 will move substantially one-quarter of a revolution, thereby causing one of said faces to engage the shoulder 82 of the bell-crank lever 80 so as to raise said lever to the position shown in Fig. 6, whereupon the continued rotation of said flange and the parts moving therewith will withdraw such one of the faces 65 from the path of the shoulder 82, as shown by Figs. 7, 8 and 5.

During the upward movement of the horizontal member of the bell-crank lever 80, as just described, the spear-head 93 thereof will engage the ledge 94 and move the armature 90 toward the electromagnet 89, and, at the conclusion of such movement of the lever 80, such spear-head will be raised sufficiently above the ledge 94 to permit movement thereof in response to the tension of the spring 92 to retain the lever 80 in its elevated position.

When the horizontal member of the bell-crank lever 80 is raised, as just described, the spacer 88 will move the contact 85 away from the contact 86 and into engagement with the contact 84, thus including the winding of the electromagnet 89 in the current path between the signaling circuit conductors 97 and 98.

If, when the electromagnet windings are thus included in the signaling circuit current path, there is sufficient current flow therethrough to cause effective energization of said magnet, the armature 90 will be moved to attracted position, against the tension of the spring 92, thus withdrawing the ledge 94 from the path of the spear-head 93, and will carry the ledge 95 into the path of the said spear-head. The lever 80 will thereupon move to the position shown in Fig. 8, where its further movement will be arrested by engagement of the spear-head 93 with the ledge 95.

When the lever 80 moves to the position shown in Fig. 8, as just described, the spacer 88 will be sufficiently withdrawn from the path of the contact 85 to permit said contact to move away from the contact 84, but not sufficiently to permit said contact 85 to move into engagement with the contact 86. When the contact 85 is in its intermediate position, as just described, the branch current path through the winding of the electromagnet 89 is interrupted, and the current flow between the conductors 97 and 98 is interrupted. Very soon after such current flow

is interrupted, as just described, the magnet 89 will be deenergized and will permit the spring 92 to swing the armature 90 away from said magnet until the movement thereof is arrested by the post 96. Such movement of the armature 90 will withdraw the ledge 95 from the path of the spear-head 93, and will thus permit the lever 80 to move from the position shown in Fig. 8 to that 10 shown in Fig. 5: thereby withdrawing the spacer 88 so as to permit the contact 85 to move into engagement with the contact 86 and thus reestablish the normal connection between the signaling circuit conductors 97 15 and 98.

If, when the horizontal portion of the lever 80 is raised by one of the faces 65, as hereinbefore described, there is no current flow in the signaling circuit of which conductors 97 and 98 form parts, or if the current flow therein is insufficient to cause effective energization of electromagnet 89, it is evident that said lever 80 will be maintained in its operated or elevated position by the 20 engagement of the ledge 94 with the spear-head 93 (as shown by Fig. 7) until such time as adequate current flow is established through the winding of said electromagnet, whereupon the armature 90 will be moved to 25 its attracted position, and the functioning of the various parts will proceed as hereinbefore more fully described.

It will be evident that,—should the characteristics of the electromagnet 89 be varied, 30 by the employment of expedients well understood by those skilled in this art, the period which will elapse between the cessation of current flow therethrough (as caused by movement of the contact 85 away from 35 the contact 84) and the retractive movement of the armature 90 resulting from such cessation, will be varied so as to alter the duration of the period during which the contact 85 will occupy its intermediate position, as 40 shown by Fig. 8. It is also evident that similar variation in the characteristics of said magnet will correspondingly alter the duration of the period which will elapse between the commencement of the application 45 of energizing current thereto and the responsive movement of the armature 90; thus determining the period during which the winding of said magnet will be included in the current path between the conductors 97 50 and 98 while the current flow therein is sufficient to cause effective energization of said magnet.

If it is desired that current responsive devices of the signaling circuit comprising the 55 conductors 97 and 98 shall be responsive to the inclusion of the winding of said magnet in the current path between said conductors, said winding should be of comparatively high resistance. In any event, it will be apparent from the foregoing that three distinct

operative conditions are established by the signal initiating device described, i. e. (1) the normal condition in which a direct, low resistance, current path is established between the conductors 97 and 98 through the 60 contacts 85 and 86; (2) an operated condition in which a comparatively high resistance current path is established from the conductor 97, through the contacts 85 and 84, the conductor 100, the winding of the electromagnet 89, the conductor 99 to the conductor 98; and (3) an intermediate condition in which the contact 85 is in its intermediate position, and current flow between the conductors 97 and 98 is therefore 65 completely interrupted.

It is also evident that such circuit changes may be utilized for causing ultimate response of devices of a signaling circuit comprising the conductors 97 and 98, even 70 if such circuit is disabled, or for any reason deenergized, at the time when the handle 29 is actuated; as the windings of the electromagnet 89 will, after any such actuation remain connected in the current path between 75 the conductors 97 and 98 until not less than a predetermined degree of energization has been applied to said magnet for a period sufficient to cause movement of the armature in response thereto and the resultant 80 movement of the lever 80; and, after such current flow has been maintained for a suitable period, the current path between the conductors 97 and 98 will be interrupted for 85 the desired period, regardless of the period 90 which may have elapsed between the actuation of the handle 29 and the occasion when a suitable current flow occurs in the conductors 97 and 98.

After actuation of the signal initiating 95 device, as hereinbefore described, one of the projections 77 of the disc 54 will be held between the latch 70 and the dog 71, as shown by Fig. 11, so as to prevent rotation of the handle 29 in either direction; unauthorized 100 repetitions of the signal are thus prevented.

When it is desired to restore the signaling mechanism to its normal condition after the utilization thereof as hereinbefore described, —the knob 38 should be grasped, reaching 105 through the opening 28, (through which access to said knob was secured upon breaking the frangible panel 31, as hereinbefore described,) and said knob should be pulled downwardly so as to withdraw the upper end 110 of the latch bolt 27 from the portion of the flange 24 engaged thereby, whereupon the upper edge of the cover 25 may be swung outwardly and said cover may then be lifted so as to withdraw the lug 26 from engagement with the portion of the flange 24 115 engaged thereby; thus effecting removal of the cover 25 from the case 21.

During such removal of the cover 25, the pin 50 will engage the enlarged head 52 of 120

post 51 and so raise said post as to lift the free end of the latch 70 out of the path of the projection 77 of the disc 54, and the spring 76 will thereupon move said latch 5 substantially lengthwise thereof toward the dog 71 until said movement of said latch is arrested when the pin 75 is brought against the side of the screw 72. As soon as the pin 50 is withdrawn from the path of the post 10 51, the spring 76 will swing the end of the latch 70 against the top of the projection 77; thus leaving the parts in condition for operation while the cover 25 is removed as, for example, for the purpose of testing said 15 mechanism.

After the cover 25 has been removed, as just described, the nut 45 should be removed from the stud 44, and the removable part comprising the side walls 40 and 41 and the 20 base wall 42 should be swung around its fulcrum on the pins 39 (and removed, if desired) so as to permit a new frangible panel to be placed in position in the recess 30 provided therefor. After such a panel 25 has been so placed in position, said member should be swung around its fulcrum pins 39 so as to bring the walls thereof against the sides of said panel, and so as to bring the ear 43 in position around the stud 44, whereupon the nut 45 should be replaced upon 30 said stud so as to firmly clamp said ear against the rear side of the cover 25. The lower edge of the cover 25 may now be placed in position, so as to permit the lug 35 26 to engage the intended portion of the flange 24, and the upper edge of said cover should then be swung to its normal position. Just before the upper edge of the cover 25 reaches its normal position during the movement 40 thereof just referred to,—the latch bolt 27 will be forced downwardly by the engagement of the beveled end thereof with the outer face of the flange 24, and will pass beneath said flange so that, when the cover 45 25 is seated against the outer side of said flange 24, the spring 36 will shoot said bolt upwardly behind said flange and thereby lock said cover in position.

While the cover 25 is being replaced in 50 position upon the case 21, as just described, the pin 50 will again engage the enlarged head 52 of the post 51 and thereby again disengage the free end of the latch 70 from the disc 54, so that if the signal initiating 55 device was actuated while the cover 25 was removed from the case 21, the handle 29 will nevertheless be unlocked for further actuation when said cover is replaced upon said case, to the end that the operability of 60 said mechanism will at all times be assured when the cover 25 is in position and carries therein an intact frangible panel 31.

Should arrangements be made whereby 65 the movement imparted to the handle 29 (or to any other setting member employed in

lieu thereof) will be at the speed or rate of movement which should be imparted to the cam faces 65, (as, for example, the arrangement shown by Figs. 14 and 15 and hereinbefore described in greater detail) the storage device and quick acting mechanism (comprising the spring 58, escapement teeth 63 and pallet 83) and the detent mechanism (comprising the flange 57, plate 66, cam 67 and member 68) may be omitted (as shown by Fig. 16); the cam faces 65 being moved, in such an event, directly with the shaft 49. If extraneous means are provided for sufficiently governing the extent and direction of the actuating movement imparted to the shaft 89 the disc 54, the latch 70 and the dog 71 may be omitted (as shown by Figs. 15 and 16).

When the signal initiating devices are employed under circumstances which do not necessitate the guarding of the operating member thereof from unauthorized manipulation, the guard comprising the cover 25 and frangible panel 31 and parts associated therewith may be suitably modified or, in some instances, dispensed with.

When the operating conditions of the signaling circuit are such that a temporary interruption or preoccupation thereof by other signals is unlikely or inconsequential, the electromagnet and escapement mechanism controlled thereby may be suitably modified and, in some instances, completely dispensed with.

Other rearrangements will readily suggest themselves to those skilled in this art, and it will be readily understood that the apparatus shown in the accompanying drawings and hereinbefore described is adapted for many different arrangements; and that while the various features and elements may be used in the combinations and relations hereinbefore specifically described, some of these may be altered and others omitted without interfering with the more general results obtained, and this invention extends to such uses.

Having now described my invention what I claim and desire to secure by Letters Patent of the United States of America is:

1. In a signaling mechanism; an extraneously operable member adapted for effective actuation only in one direction, a latch arranged to engage said member to limit movements thereof in said direction to a predetermined operative cycle, ratchet mechanism arranged to engage said member during each such cycle of its actuation to prevent reverse movement thereof, and extraneously operable means for disengaging said latch.

2. In a signaling mechanism; a signal initiating device having a member manually operable for causing said device to accomplish a definite cycle of action, a cover nor-

5 mally obstructing and movable to permit access to said member, a latch for rendering said device functionally unresponsive to said member, and means operable by said 5 cover to condition said latch to permit functional responsiveness of said device to manual operation of said member.

10 3. In a signaling mechanism; signal initiating means, actuating means therefor including a movable member and means for causing a definite cycle of operation of said initiating means upon a predetermined movement of said movable member, manually operable means for moving said member, latching means for preventing more than said predetermined movement of said movable member, means for obstructing access to said manually operable means and including a cover movable to permit such access, and means operable by movement of said cover to release said latching means.

15 4. In a signaling mechanism; an operating member adapted for effective actuation in one direction, extraneously operable means for governing the occurrence of such effective actuation, means for preventing reverse actuation of said member, latching means for limiting each actuation of said member in said first named direction to a predetermined amount, means for obstructing access to said member and including a cover movable to permit such access, means operated by movement of said cover to momentarily render said latching means ineffective, and means including said latching means for maintaining such ineffectiveness until after further actuation of said member for said predetermined amount.

20 5. In a signaling mechanism; an operable member adapted for effective movement in one direction, means for preventing reverse movement of said member, latching means arranged for arresting the effective movement of said member at predetermined points therein, means for obstructing access to said member and including a cover movable to permit such access, means operated by movement of said cover to momentarily render said latching means ineffective, and means including said latching means for maintaining said ineffectiveness until after further effective movement of said member.

25 6. In a signaling mechanism; a signal initiating device having a definite cycle of action and responsive to a manually operable member thereof, means for preventing movement of said member in one direction, means for limiting the extent of each movement in the other direction to that of said definite cycle, a guard for protecting said manually operable member from unauthorized actuation, and means including said second named means operable incident to manipulation of said guard for rendering said

device responsive to its manually operable member for a further such cycle.

30 7. A signaling mechanism having a definite cycle of action and responsive to a manually operable member thereof, a frangible panel normally obstructing access to said member, a support for said panel comprising a part removable for the purpose of permitting replacement of said panel, normally ineffective latching means arranged to act at the conclusion of operative cycles of said signaling mechanism to prevent repetitions of such cycles, releasing means for said latching means operable by the removal or replacement of said support for rendering said latching means ineffective, and means including said latching means for continuing attained ineffectiveness of said latching means throughout periods of inactivity of and in the absence of fulfillment of the cycle of action of said signaling mechanism.

35 8. A signaling mechanism having a definite cycle of action and responsive to a manually operable member thereof, a frangible panel normally obstructing access to said member, a support for said panel comprising a part removable for the purpose of permitting replacement of said panel, fastening means for said part operable to permit unfastening thereof and so positioned that access thereto is obstructed by said panel, normally ineffective latching means arranged to act at the conclusion of operative cycles of said signaling mechanism to prevent repetitions of such cycles, releasing means for said latching means operable by the removal or replacement of said support for rendering said latching means ineffective, and means including said latching means for continuing attained ineffectiveness of said latching means throughout periods of inactivity of and in the absence of the fulfillment of the cycle of action of said signaling mechanism.

40 9. In a signaling mechanism; a setting member adapted for rapid or slow operation thereof, an operating member, a storage device for imparting to said operating member actuating energy imparted to said device by said setting member, a detent normally restraining and arranged to be disengaged from said operating member to permit movement thereof when said setting member has been sufficiently moved to impart enough energy to said storage device for causing predetermined actuation of said operating member, a projection moving with said setting member, a latch movable into and out of the path of said projection and also movable along the path of said projection, means for limiting the movement of said latch along the path of said projection, means for urging said latch into the path of said projection and for yieldingly resisting

movement imparted to said latch along the path of and by said projection, a governor for regulating the speed of said operating member, and circuit controlling contacts responsive to the actuation of said operating member.

10. In a signaling mechanism; signaling contacts constantly urged to assume a predetermined normal relationship, means for 10 variously altering the relationship of said contacts, and magnetically controlled mechanism for progressively governing the restoration of said contacts from such altered to such normal relationship.

15. 11. In a signaling mechanism; signaling contacts constantly urged to assume a predetermined relationship, quick-acting means for effecting a second relationship of said contacts, and magnetically controlled mechanism for governing the attainment of a 20 third relationship of said contacts.

25. 12. In a signaling mechanism; signaling contacts constantly urged to assume a predetermined normal relationship, quick-acting means for effecting an abnormal relationship of said contacts, and magnetically controlled step by step mechanism for governing the restoration of said contacts from such abnormal to an intermediate and to 30 said normal relationship.

35. 13. In a signaling mechanism; signaling contacts, means for successively imparting differing adjustments thereto, actuating mechanism operable to cause said means to impart one of said adjustments to said contacts and to set said means for the accomplishment of other of such adjustments, and magnetically controlled step by step mechanism for releasing said actuating mechanism for successively accomplishing such 40 other adjustments.

45. 14. In a signaling mechanism; circuit controlling contacts constantly urged to assume predetermined relationships operating mechanism for momentarily revising the relationships of said contacts, an electromagnet, and an escapement controlled by said magnet for so governing said operating mechanism as to thereby retain said contacts in such revised relationships if said magnet is deenergized at the time of said revision, and to permit said contacts to assume intermediate relationships upon the energization of said magnet and to there- 50 after return to their normal relationships upon the subsequent deenergization of said magnet.

60. 15. In a signaling mechanism; circuit controlling contacts constantly urged to assume predetermined relationships and suited for actuation for revision of such relationships, an operating mechanism having a definite operative cycle and arranged to momentarily cause the actuation of said contacts to revise the relationships thereof dur- 65

ing each operative cycle of said operating mechanism, a storage device constructed and arranged for setting thereof to deliver energy for causing such a cycle of said operating mechanism, a setting member arranged for actuation thereof to so set said device, a detent normally restraining and arranged to be disengaged from said operating mechanism upon such actuation of said setting member, an escapement operable to 75 so govern said operating mechanism as to thereby retain said contacts in the revised relationships to which they may be momentarily actuated by said operating mechanism, and to successively permit said contacts to assume intermediate relationships and to thereafter assume the relationships toward which they are urged, and an electromagnet so arranged that, upon energization and de-energization thereof, it will cause such successive operation of said escapement.

70. 16. In a signaling mechanism; circuit controlling contacts constantly urged to assume predetermined relationships and suited for actuation for revision of such relationships, 90 an operating mechanism having a definite operative cycle and arranged to cause actuation of said contacts to revise the relationships thereof during each such operative cycle, a governor arranged to so regulate the speed of 95 said operating mechanism that said contacts will be thereby maintained in actuated relationship for a substantially uniform predetermined period during each operative cycle of said operating mechanism, a storage device constructed and arranged for setting thereof to deliver energy for causing such a cycle of said operating mechanism, a setting member arranged for actuation thereof to 100 so set said device, a detent normally restraining and arranged to be disengaged from said operating mechanism upon such actuation of said setting member, an escapement operable to so govern said operating mechanism as to thereby retain said contacts in the revised relationship to which they may be actuated by said operating mechanism, and to successively permit said contacts to assume intermediate relationships and to thereafter assume the relationships toward which they are urged, and an electromagnet so arranged 105 that, upon energization and deenergization thereof, said magnet will cause such successive operation of said escapement.

110. 17. In a signaling mechanism; circuit controlling contacts constantly urged to assume predetermined relationships and suited for actuation for revision of such relationships, an operating mechanism having a definite cycle and arranged to momentarily cause the actuation of said contacts to revise the relationships thereof during each such operative cycle, a storage device constructed and arranged for setting thereof to deliver energy 115 for causing such a cycle of said operating 120

- mechanism, a setting member arranged for actuation thereof to so set said device, a projection moving with said setting member, a latch for cooperation with said projection for limiting operation of said operating mechanism to the aforesaid cycle, said latch movable into and out of the path of said projection and also movable along the path of said projection, means for urging said latch into the path of said projection and for yieldingly resisting movement imparted to said latch along the path of said projection, an escapement operable to so govern said operating mechanism as to thereby retain said contacts in the revised relationships to which they may be momentarily actuated by said operating mechanism, and to successively permit said contacts to assume intermediate relationships and to thereafter assume the relationships toward which they are urged, and an electromagnet so arranged that, upon energization and deenergization thereof, said magnet will cause such successive operation of said escapement.
18. In a signaling mechanism; a setting member, an operating mechanism, a storage device for imparting to said mechanism actuating energy imparted to said device by said setting member, a detent normally restraining and arranged to be disengaged from said operating mechanism to permit predetermined movement thereof when said setting member has been sufficiently moved to impart enough energy to said storage device for causing such predetermined actuation of said operating mechanism, means for preventing reversal of such movement of said setting member which has caused disengagement of said detent, a projection moving with said setting member, a latch movable into and out of the path of said projection and also movable along the path of said projection, means for limiting the movement of said latch into the path of said projection and for yieldingly resisting movement imparted to said latch along the path of and by said projection, a governor for regulating the speed of said operating mechanism, circuit controlling contacts constantly urged to assume predetermined relationships and arranged for response to and during the actuation of said operating mechanism to momentarily revise the relationships of said contacts, an electromagnet, and an escapement controlled by said magnet for so governing said operating mechanism as to thereby retain said contacts in such revised relationships if said magnet is deenergized at the time of such revision, and to permit said contacts to assume intermediate relationships upon the energization of said magnet and to thereafter return to their normal relationships upon the subsequent deenergization of said magnet.
19. In a signaling mechanism; a setting member adapted for rapid or slow operation thereof, an operating mechanism, a storage device for imparting to said operating mechanism actuating energy imparted to said device by said setting member, a detent normally restraining and arranged to be disengaged from said operating mechanism to permit predetermined movement thereof when said setting member has been sufficiently moved to impart enough energy to said storage device for causing such predetermined actuation of said operating mechanism, means for preventing reversal of such movement of said setting member which has caused disengagement of said detent, a projection moving with said setting member, a latch movable into and out of the path of said projection and also movable along the path of said projection, means for limiting the movement of said latch into the path of said projection, means for urging said latch into the path of and by said projection, a governor for regulating the speed of said operating mechanism, circuit controlling contacts constantly urged to assume predetermined relationships and arranged for response to and during the actuation of said operating mechanism to momentarily revise the relationships of said contacts, an electromagnet, and an escapement controlled by said magnet for so governing said operating mechanism as to thereby retain said contacts in such revised relationships if said magnet is deenergized at the time of such revision, and to permit said contacts to assume intermediate relationships upon the energization of said magnet and to thereafter return to their normal relationships upon the subsequent deenergization of said magnet.
20. In a signaling mechanism; a setting member adapted for rapid or slow operation thereof, an operating mechanism, a storage device for imparting to said operating mechanism actuating energy imparted to said device by said setting member, a detent normally restraining and arranged to be disengaged from said operating mechanism to permit predetermined movement thereof when said setting member has been sufficiently moved to impart enough energy to said storage device for causing such predetermined actuation of said operating mechanism, means for preventing reversal of such movement of said setting member which has caused disengagement of said detent, a projection moving with said setting member, a latch movable into and out of the path of said projection and also movable along the path of said projection, means for limiting the movement of said latch into the path of said projection, means for urging said latch into the path of and by said projection, a governor for regulating the speed of said operating mechanism, circuit controlling contacts constantly urged to assume predetermined relationships and arranged for response to and during the actuation of said operating mechanism to momentarily revise the relationships of said contacts, an electromagnet, and an escapement controlled by said magnet for so governing said operating mechanism as to thereby retain said contacts in such revised relationships if said magnet is deenergized at the time of such revision, and to permit said contacts to assume intermediate relationships upon the energization of said magnet and to thereafter return to their normal relationships upon the subsequent deenergization of said magnet.

said projection and for yieldingly resisting movement imparted to said latch along the path of and by said projection, a governor for regulating the speed of said operating mechanism, circuit controlling contacts constantly urged to assume predetermined relationships and arranged for response to and during the actuation of said operating mechanism to momentarily revise the relationships of said contacts, an electromagnet one end of the winding of which is connected to one of said contacts, and an escapement controlled by said magnet for so governing said operating mechanism as to thereby retain 10 said contacts in such revised relationships if said magnet is deenergized at the time of such revision, and to permit said contacts to assume intermediate relationships upon the energization of said magnet and to thereafter 20 return to their normal relationships and upon the subsequent deenergization of said magnet.

21. In a signaling mechanism; setting member adapted for rapid or slow operation thereof, an operating member, a storage device for imparting to said operating member actuating energy imparted to said device by said setting member, a detent normally restraining and arranged to be disengaged 25 from said operating member to permit movement thereof when said setting member has been sufficiently moved to impart enough energy to said storage device for causing predetermined actuation of said operating member, means for preventing reversal of 30 such movement of said setting member which has caused disengagement of said detent, a projection moving with said setting member, a latch movable into and out of the path of said projection and also movable along the path of said projection, means for limiting the movement of said latch along the path of said projection and also movable along the path of said projection, means for urging said latch into the path of said projection and 40 for yieldingly resisting movement imparted to said latch along the path of and by said projection, a governor for regulating the speed of said operating member, circuit controlling contacts, actuating means for said 45 contacts constantly urged for movement in one direction to the normal position thereof and responsive to said operating member for movement in the other direction to a predetermined abnormal position and release thereof during the operation of said operating member, an electromagnet one end of the winding of which is connected to one of said contacts, and an escapement controlled 55 by said magnet for retaining said actuating means in the position to which it is moved during such response of said operating member, said escapement being arranged to permit said actuating means to move to an intermediate position upon the energization of 60 said magnet and to thereafter return to its

normal position upon the subsequent deenergization of said magnet.

22. In a signaling mechanism; a manually operable member; a frangible panel normally obstructing access to said member; a support for said panel comprising a part removable for the purpose of permitting replacement of said panel, and fastening means for said part operable to permit unfastening thereof and so positioned that access thereto is obstructed by said panel; an operating member; a storage device for imparting to said operating member actuating energy imparted to said device by said setting member, a detent normally restraining and arranged to be disengaged from said operating member to permit movement thereof when said setting member has been sufficiently moved to impart enough energy to said storage device for causing predetermined actuation of said operating member, means for preventing the reversal of such movement of said manually operable member which has caused disengagement of said detent; a projection moving with said manually operable member; a latch movable into and out of the path of said projection and also movable along the path of said projection; means for limiting the movement of said latch along the path of said projection; means for urging said latch into the path of said projection and for yieldingly resisting movement imparted to said latch along the path of and by said projection; a governor for regulating the speed of said operating member; circuit controlling contacts; actuating means for said contacts constantly urged for movement in one direction to the normal position thereof and responsive to said operating member for movement in the other direction to a predetermined abnormal position and release thereof during the operation of said operating member; an electromagnet one end of the winding of which is connected to one of said contacts; an escapement controlled by said magnet for retaining said actuating means in such abnormal position, said escapement being arranged to permit said actuating means to move to an intermediate position upon the energization of said magnet and to thereafter return to its normal position upon the subsequent deenergization of said magnet; and means operable by movement of the frangible panel support for withdrawing said latching means from the path of the projection engaged thereby.

23. In a signaling mechanism; a main line current path, a branch current path, an electromagnet included in said branch path, circuit controlling means for said paths normally biased to close said main path and to break said branch path, quick-acting mechanism operable to momentarily actuate

5 said means to reverse the conditions of said paths, and a step by step escapement operable by said magnet and arranged to so govern said quick-acting mechanism as to maintain said means in such actuated position during deenergization of said magnet, to permit action of said means to restore one of said paths upon energization of said magnet and to thereafter permit action of 10 said means to restore the other of said paths upon subsequent deenergization of said magnet.

15 24. In a signaling mechanism; a main line current path, a branch current path, an electromagnet included in said branch path, a circuit controlling means for said paths normally biased to close said main path and to break said branch path, quick-acting mechanism operable to momentarily actuate said means to break said main path and to close 20 said branch path, and a step by step escapement operable by said magnet and arranged to so govern said quick-acting mechanism as to maintain said means in such actuated position during deenergization of said magnet, and to permit action of said means to break said branch path upon energization of said magnet, and to thereafter permit action of said means to close said main path upon the resulting deenergization of said 25 magnet.

24 In witness whereof, I hereunto subscribe my name, this 22nd day of November, 1920.

NATHAN H. SUREN.
